UNITED STATES PATENT OFFICE.

ALFIO GRASSO, OF LIVORNO, ITALY.

MACHINE FOR HEATING THE SURFACE OF ROADS FOR COVERING THE SAME WITH
POURED ASPHALT.

1,122,384.

Specification of Letters Patent. Patented Dec. 29, 1914.

Application filed March 17, 1913. Serial No. 755,054.

To all whom it may concern:

Be it known that I, ALFIO GRASSO, a subject of the King of Italy, and resident of 4 Piazza Cappellini, Livorno, Tuscany, Italy, 5 have invented certain new and useful Improvements in Machines for Heating the Surface of Roads for Covering the Same with Poured Asphalt, of which the following is a specification.

10 The present invention relates to a wheeled machine which is intended to be used for heating the surface of the road for covering the same with poured asphalt.

For applying a poured layer of asphalt 15 on roads it is necessary to previously heat the surface of the road to a suitable temperature. It is for this purpose, that the machine of the present invention is intended.

The invention consists essentially in that 20 the hot gases from one or several stoves arranged on the machine are conducted beneath the bottom of the machine, which bottom is situated above the surface of the road, and which has hinged gates at the sides, 25 reaching down almost to the road surface. By such means a kind of hood is formed over the respective part of the road, beneath which the hot gases can have a greater effect.

30 The hot gases are forced under the bottom of the machine by a blast produced by a fan driven by an engine. Preferably this engine is also employed for advancing the machine. The machine is also provided 35 with a tank in which the asphalt is melted by the heat of the stoves, and from which the asphalt may flow on to the surface of the road.

In the accompanying drawing a constructional form of the machine according to 40 the present invention is exemplified.

Figures 1 and 1^a constitute a longitudinal section on the line I—I in Fig. 2. Figs. 2 and 2^a constitute a plan, partly in section 45 on the line II—II in Fig. 1.

The machine consists essentially of a box-shaped body 1, which is preferably made of angle-irons and is covered with metallic plates. The body runs on four wheels 2, 2 50 and 3, 3 and the front wheels of these, 2, 2 can be turned by means of a steering wheel 4 in known manner, for steering the car. On the body 1 are arranged several tanks, of which tank 5 may serve as a water tank,

tank 6 as fuel tank, tank 7 as asphalt tank, 55 and tank 8 as mineral oil tank. On the forward part of the body 1 is arranged a combustion engine 9, which serves various purposes. From the engine 9 a fan 10 is driven by suitable gearing, which fan may be engaged and disengaged at will by means of a hand wheel 11. To the delivery pipe of the fan is connected a pipe 12, which leads to two stoves arranged on the rear part of the body 1. Each of these stoves may consist of a castiron body 13, which is surrounded by a metal shell 14. The air passing from the pipe 12 into the stoves will flow from above and from the side into the fire on the grate 15. The air supply is controlled by means of a valve 16. The fuel is introduced into the stove through a door 17, and a lower door 18 is provided for cleaning the stove. The hot gases are carried downward by the blast and are spread 70 by a spreader 19. They then pass under the bottom 20 of the body 1, which bottom is about 15 centimeters=6 inches above the surface of the road. For keeping the hot gases together under the latter and forcing 75 them to act on the surface of the road gates 21 are provided at the lower edges of the body, which gates reach almost down to the surface of the road and can be adjusted according to requirement. For this purpose 80 the gates 21 are held by means of chains or the like. The hot gases are then allowed to escape through suitably provided openings. The engine 9 at the same time serves to uniformly advance the whole machine. For 85 this purpose a crank 22 is fitted to the free end of the engine shaft, and the crank pin is connected to the one end of a member 23. The other end of said member 23 engages with a vertical rocking bar 24, the member 23 being hinged to a screwing sleeve 25, 90 which screws on a thread on said rocking bar 24. Below this sleeve 25 is arranged a second sleeve 26, which is connected by a member 27 to a pin 28.

The bar 24 has both right and left hand threads, so that when it is turned by means of a hand wheel 29 the two sleeves 25 and 26 may be approached to or removed from each other. By the adjustment of sleeve 25 the 105 size of the stroke of the bar 24 is controlled. By these means the rotary motion of the engine shaft is transmitted to a shaft 30.

From the latter the rotation is transmitted by an endless chain 31 to the rear axle 32, which propels the vehicle.

- As already stated, the bar 24 has right and left hand threads, so that the two sleeves 5 can be approached to and removed from each other for varying the speed, say for varying the travel of the machine between 10 and 100 meters per minute. The speed of the machine must be varied accordingly as a large or small piece of gravel covered road is to be heated for asphalting. Between the two stoves a boiler 39 is arranged, in which the asphalt to be poured is melted by the heat radiating from the two stoves. While 15 the machine is slowly advancing the molten asphalt runs out through cock 40 on to the surface of the road, where it is evenly distributed and rolled down.
- For quickly returning the machine to its starting point after it has traveled a distance corresponding to its size, a sprocket wheel 33 is fitted to the engine shaft, from which wheel the motion is transmitted by 20 means of an endless chain 34 to a gearing, which is arranged in the casing 35. For changing from the slow advance of the machine to the fast return it is necessary to sever the connection between the member 27 25 and the pin 28. Then the gearing contained in the casing 35 is engaged by means of levers 37 and 38 of which the one controls the reversing of the gear and the other the changing of the speed. From this gearing 30 the shaft 30 is driven, from which the chain 31 transmits, as hereinbefore described, the motion to the rear axle 32. During the return of the machine and for treating a fresh strip of road, the fan 10 is of course first dis-

connected and the gates 21 are raised, so that they do not come into contact with the road surface. The hereinbefore described arrangement also serves to advance the machine on ordinary roads. For facilitating the transport the journals of the wheels 2 45 and 3 are vertically adjustable in guides 41, so that the whole body of the car can be lifted from the ground and will not strike against any obstructions on the road. The bearings are adjusted in the guides 41 in 50 known manner by means of screw spindles.

I claim:

A machine of the kind described comprising a box-shaped frame, reaching nearly down to the surface of the road, wheels on said frame, and stoves arranged on the latter, a fan driven by an engine and producing a current of air adapted to force the hot gases from said stoves under said box-shaped frame, said frame having gates 55 hinged to the latter, and reaching nearly down to the surface of the road, and adapted to retain the hot gases within said box-shaped frame, a tank arranged on said frame and adapted to have the asphalt melted 60 therein by the heat of said stoves, and means for distributing the melted asphalt from said tank on to the surface of the road heated by said hot gases.

In testimony whereof I have hereunto 70 signed my name this 24th day of February 1913, in the presence of two subscribing witnesses.

ALFIO GRASSO.
